UNITED STATES PATENT OFFICE.

LEON W. NICHOLS AND WALTER LEEDY, OF YOUNGSTOWN, OHIO.

VENTILATOR.

1,412,063.

Specification of Letters Patent. Patented Apr. 11, 1922.

Application filed July 16, 1919. Serial No. 311,235.

To all whom it may concern:

Be it known that we, LEON W. NICHOLS and WALTER LEEDY, citizens of the United States, residing at Youngstown, in the county of Mahoning and State of Ohio, have invented certain new and useful Improvements in Ventilators, of which the following is a specification.

This invention relates to ventilators, principally of that type which is rotatably mounted upon the top of an air stack or shaft, the object being to provide a contrivance which will avoid all back draft while the structure is adjusting itself to changes in the direction of the wind, thus preventing any downward rush of foul air, smoke or other substance, caused by the blowing of the wind in the rear or discharge end of the ventilator during the time in which the structure is revolving in response to the changing currents of the air or direction of the wind.

Figure 1 is a perspective view of our invention; Figure 2 is a vertical longitudinal section; Figure 3 is a horizontal longitudinal section on line 3—3 Figure 2; Figure 4 is a horizontal transverse section on line 4—4 Figure 2; Figure 5 is a fragmentary view, partially in section, showing the closing 30 weight bars attached to the louvers.

a represents the base of the structure which is rigidly secured to the upper end of the ventilator shaft, and is provided with the flaring flange shield or cowl *b*. *c—c* are cross bars rigidly secured within the base *a*, there being an upper and a lower series of the same. At the intersection of the lower series of said cross bars is the bearing block *d* having a central opening, while at the intersection of the upper series is the bearing block *e* having a central opening, and also provided in its upper face with the ball-race *f*. Rigidly mounted in the bearing blocks *d* and *e* is a perpendicular spindle *g* which extends the full height of the structure. *h* represents the lower part of the rotating portion of the structure and is provided with a flaring flange shield or cowl *i*, and also with a cross bar *j*. To the center 50 of the cross bar *j* is secured the bearing block *k*, having a central opening, and being recessed in its lower face, thus providing an outer flange or wall to embrace the bearing block *e* with the ball-race in its upper face. *l* represents the top, *m* the bottom and *n—n* the sides of the upper portion of the struc-

ture. At the front end of this open frame work is a triangular body *o*, rigidly secured in spaced relation with the slides *n—n*, and with its apex extending out beyond the frame work. Secured to the inner face of the top *l* is the bearing block *p* having a conical bearing recess in its lower face to receive the upper end of the spindle *g*.

At the rear or discharge end of the structure we provide a series of blades or louvers *q—q*, swingingly mounted at their upper edges (as at *r*) to the sides *n—n*.

To the inside of each one of the louvers, we attach a counter-weight *s* of sufficient weight to hold the louver normally open, preferably at an angle of about forty-five degrees.

A vane *t* is secured to the top of the structure to cause it to revolve as the course or direction of the wind changes.

The entire rotatable portion of the device is mounted upon the base *a* by passing the spindle *g* through the opening in the bearing block *h*, the upper end of the bearing block *e*, with the ball-race in its upper face, 80 registering in the recess in the lower face of block *h*, while the upper end of the spindle *g* engages the conical recess in the lower face of the block *p* attached to the inside of the top *l*.

As already stated, the primary purpose and object of our device is to provide means of preventing back drafts or currents through the ventilator, and the operation of our device is as follows:

When the structure is adjusted in line with the direction of the wind the air enters at the front end between the triangular body *o* and the sides *n—n*, passing over the ventilator shaft and out at the rear end between the louvers *q—q*, which, as already stated, are held open by counter-weights *s—s*, carrying with it the foul and obnoxious air and gases drawn upwardly from the air shaft by the current passing over it. Upon any sudden change in the direction of the wind, however, or when eddies or contrary currents of air occur, causing the air to blow against the rear end of the structure, the louvers are forced downwardly to a closed position against the resistance of the counter-weights *s—s*, thus preventing any back draft or rear-ward movement of the air through the ventilator, which inevitably drives the foul and poisonous air down the ventilating shaft.

When the structure has shifted in re-

response to the change of the wind the current against the louvers will cease, when they will be raised to their open position by the counter-weights.

5 We claim—

1. In a device of the character described, a casing open at both ends rotatably mounted upon a ventilator shaft, and provided at its discharge end with one or more 10 swingingly mounted louvers adapted to be held normally open, but to be automatically closed by any reverse current approaching the discharge end.

2. In a device of the character described, 15 a casing open at both ends rotatably mounted upon a ventilator shaft, and provided at its intake end with an inner triangular body in spaced relation with the sides of said casing, and at its discharge end with one or more 20 swingingly mounted louvers adapted to be held normally open, but to be automatically closed by any reverse current approaching the discharge end.

3. In a device of the character described, 25 a casing open at both ends rotatably mounted upon a ventilator shaft, and provided at

its discharge end with one or more swingingly mounted louvers, each of said louvers being provided with a counter-balance to hold it normally open, but adapted to be automatically closed by any reverse current 30 approaching the discharge end.

4. In a device of the character described, a casing open at both ends rotatably mounted upon a ventilator shaft, and provided at 35 its intake end with a triangular body in spaced relation with the sides of said casing, and at its discharge end with one or more swingingly mounted louvers, each of said louvers being provided with a counter- 40 weight to hold it normally open, but adapted to be automatically closed by any reverse current approaching the discharge end.

In testimony whereof we hereunto affix our signatures in the presence of two wit- 45 nesses.

LEON W. NICHOLS.
WALTER LEEDY.
